UNITED STATES PATENT OFFICE

95,891

DESIGN FOR A VENDING MACHINE CABINET

Rowland Bentley, Mount Airy, and Benedict
Bentley, Gladwyn, Pa.

Application March 25, 1935, Serial No. 56,043

Term of patent 14 years

To all whom it may concern:

Be it known that we, Rowland Bentley and Benedict Bentley, citizens of the United States, residing at Mount Airy, in the county of Philadelphia, State of Pennsylvania, and Gladwyn, in the county of Montgomery, State of Pennsylvania, respectively, have invented a new, original, and ornamental Design for a Vending Machine Cabinet, of which the following is a specification, reference being had to the accompanying drawing, which forms a part hereof.

elevation and Figure 3, a side elevation of a cabinet embodying the new and improved design.

We claim:

The ornamental design for a vending machine cabinet, substantially as shown.

ROWLAND BENTLEY.
